(57) **CLAIM**

The ornamental design for a pedal switch for surgical navigation device, as shown and described.

DESCRIPTION

FIG. 1 is a perspective view of a pedal switch for a surgical navigation device showing our new design;
 FIG. 2 is a front elevation view thereof;
 FIG. 3 is a rear elevation view thereof;
 FIG. 4 is a first side elevation view thereof;
 FIG. 5 is a second side elevation view thereof;
 FIG. 6 is a top plan view thereof; and,
 FIG. 7 is a bottom plan view thereof.

The broken lines show portions of the design that form no part of the claimed design.
